ATTORNEY

UNITED STATES PATENT OFFICE.

GEORGE F. KOLB, OF PHILADELPHIA, PENNSYLVANIA.

CARPET-STRETCHER AND TACK DRIVER AND EXTRACTOR.

SPECIFICATION forming part of Letters Patent No. 365,823, dated July 5, 1887.

Application filed December 23, 1885. Serial No. 186,527. (No model.)

To all whom it may concern:

Be it known that I, GEORGE F. KOLB, a citizen of the United States, residing in the city and county of Philadelphia, State of Pennsylvania, have invented a new and useful Improvement in Carpet - Stretchers and Tack Drivers and Extractors, which improvement is fully set forth in the following specification and accompanying drawings, in which—

10 Figure 1 represents a perspective view of a carpet-stretcher, &c., embodying my invention. Fig. 1^a represents a sectional view of a portion of the stretcher in line *xx*, Fig. 1, on an enlarged scale.

15 Similar letters of reference indicate corresponding parts in the two figures.

My invention consists of a device, substantially as hereinafter described, whereby carpets may be stretched and tacks driven.

20 It also consists of a combined carpet-stretcher, tack-driver, and tack-extractor.

Referring to the drawings, A represents a plunger or sliding hammer, which is constructed of a rod or bar of any suitable material, the lower end whereof or head A' is formed of magnetic iron or other metal, the said hammer being fitted to a stock, B, which in Fig. 1 is tubular.

25 C represents a carpet-stretcher, which is formed with a toothed edge, D, at its lower end and connected at its upper end with the stock B, whereby the latter forms a handle for the hammer and the carpet-stretcher. The upper end of the stretcher is tubular, in order 30 to permit the passage of the hammer therethrough. The main portion of the stretcher is open, so that access is had to the head of the hammer for feeding the same with tacks, which, as is evident, will be held by their 35 heads by attraction, the points being in advance. The stock is provided with a knob, B², at its upper end for convenience of handling the implement, and carries a spring, E, which presses against the hammer for forcibly depressing the same, although it is evident that the hammer may be dropped by 40 gravity. Connected with the hammer is a handle or knob, F, whereby the hammer may be set preparatory to operation, and the upper end of the stretcher or any portion of the

stock has an L-shaped slot, F', in order to receive said knob and hold the hammer in operative position. When the parts are in position shown in Fig. 1, the carpet may be conveniently and effectively stretched, and when this is accomplished the knob F is released, whereby the hammer drops, and carrying the tack with it, drives it into the carpet. The hammer is again raised and another tack applied to the head thereof, after which the operation of carpet-stretching and tack-driving may be repeated. The serrated end of the stretcher is angular, forming a flange, G, which serves as a tack-extractor. The teeth of the flange are inserted under the head of a driven tack, and by operating the stock, using the bend of the flange as a fulcrum, the tack will be easily and quickly lifted or extracted.

I am aware that it is not new to construct a combined carpet - stretcher and tack - driver having a tubular stock with prongs and a plunger operated by a spring within a handle, which handle slides on said stock, the said plunger operating to drive the tack, and such I do not claim.

Having thus described my invention, what I claim as new, and desire to secure by Letters Patent, is—

1. A combined carpet stretcher, tack driver and extractor having a stretcher with a bent lower portion having a serrated edge and an L-shaped slotted upper portion, a handle working in a tubular stock secured to the stretcher, said handle having a knob adapted to rest in said slot when the handle is raised, and a spring adapted to operate said handle, substantially as described.

2. In a combined carpet-stretcher and tack-driver, the stretcher having the L-shaped slot F', and provided with a tubular stock having knob B², in combination with the sliding hammer A, having knob F, the magnetic head A', and spring E, located in said stock between said hammer and knob B², all substantially as described.

GEORGE F. KOLB.
